UNITED STATES PATENT OFFICE.

JAMES McLAIN TAYLOR, OF NEW YORK, N. Y.

LOCK FOR MOTORS.

Application filed August 24, 1920. Serial No. 405,582.

To all whom it may concern:

Be it known that I, JAMES M. TAYLOR, a citizen of the United States, and a resident of the city of New York, borough of Manhattan, in the county and State of New York, have invented a new and Improved Lock for Motors, of which the following is a full, clear, and exact description.

The present invention relates to new and useful improvements in devices for locking motor vehicles, and it pertains more particularly to a mechanism adapted to render inoperative the fuel and ignition supply system of the motor of said vehicle.

It is one of the primary objects of the present invention to provide a device whereby the supply of fuel to a carburetor of the internal combustion motor may be entirely shut off, thus rendering the motor inoperative.

It is a further object of the invention to provide means in combination with the fuel control for breaking the ignition circuit to further render the motor inoperative.

It is a further object of the invention to provide a device which includes a locking mechanism constructed in such a manner that after it has once been opened, the key may be removed, the structure being such as to permit of an automatic locking of the mechanism when moved to the inoperative position.

It is a still further object of the present invention to so construct a device of this character that the same will be readily adaptable to motor vehicles at present in use without materially changing their mechanisms or designs.

With the above and other objects in view, reference is had to the accompanying drawings, in which—

Figure 1 is a front elevation partly broken away of a device constructed in accordance with the present invention;

Fig. 2 is a longitudinal sectional view thereof;

Fig. 3 is a detail top plan view;

Fig. 4 is a sectional view taken on the line 4—4 of Fig. 2, with the several parts in their locked position;

Fig. 5 is a similar view with the parts in their open position;

Fig. 6 is a detail sectional view taken on the line 6—6 of Fig. 2, with the parts

of the locking mechanism in their locked position;

Fig. 7 is a similar view with the parts in their open position;

Fig. 8 is a rear elevation of the device.

Referring more particularly to the drawings, the gas line of the motor is indicated by the reference character 10, and mounted in said gas line 10, is a valve chamber 11. This valve chamber 11 has an inlet passage 13 and an outlet passage 12, and has its bottom wall closed by means of a plug 14, said plug serving to permit of access to the chamber 11 for the purpose of draining and cleaning the same. Reciprocatively mounted within the chamber 11, is a piston valve 15, and said piston valve is adapted to open the inlet 13 to the outlet 12, or to close communication between the inlet and outlet ports depending upon its position in the chamber or casing 11. Projecting vertically from the casing 11 is a tubular member 16, and fitting in the upper end of said tubular member 16 is a flexible tubular member 17, upon the upper end of which is secured another tubular member 18.

Mounted upon the upper end of the tubular member 18 is the yoke extension 19 of a housing 20, said housing being circular in cross sectional form. Mounted in the housing 20 is a rotating member 21, and said rotating member is provided with thumb pieces 22, by means of which it is grasped in order that it may be rotated.

Projecting from the rear face of the rotating member 21, is a pin 23 and pivotally connected to said pin 23, is a crank or lever 24. The lower end of this crank or lever 24 is bifurcated as at 25, and mounted in the bifurcated end 25 of said crank 24, is a tubular member 26. This tubular member 26 is connected to a flexible shaft 27, the lower end of which is secured within a tubular member 28, which in turn is secured to the valve member 15 by means of a bolt or the like 29.

By this construction it will be noted that as the member 21 is rotated within the housing 20, through the medium of the flexible shaft 27 and its several connections and the crank 24, the valve member 15 will be reciprocated in the valve chamber 11 to either open or close the outlet port 12.

The rotating member 21 has a tubular ex-

tension 30 and mounted in said tubular extension 30 is a lock 31, which lock is adapted to be operated by means of a key inserted into the keyhole slot 32. The keyhole slot 32 is adapted to be protected from the weather by means of a cover plate 33, and said cover plate 33 is provided with an operating projecting member 34, by means of which it is moved about its pivotal point 35 to open and close the keyhole slot 32.

Mounted in the rotating member 21, is a plunger 40, adapted to have its free end projected into a recess 41 through one of the walls of the rotating member 21, to prevent rotary movement of the said member 21 in its mounting. This reciprocating member 40 is rigidly mounted in a housing 42, and interposed between said housing and a cup 43, is a coil spring 44, which coil spring serves to maintain the reciprocating member 40 in the recess 41 when the same are in register with each other. In order to position the plunger 40 within the rotating member 21, a closing bolt 45 is employed, said bolt having screw-threaded engagement with an opening in the top of the housing 20.

The lock 31 is adapted to actuate a cam member 46 and in its rotation said cam member 46 is adapted to engage the housing 42 to move the reciprocating member 40 out of the recess 41 to permit of a free movement of the rotary member 21 within the housing 20. The housing 20 is provided at opposite points on its interior with lugs 52 and 53, and carried by the rotating member 21 in such position as to engage these lugs to limit the rotating movement of the member 21, is a projecting pin or lug 55.

The reference character 56 designates a rear closing plate for the housing 20, and mounted as shown in Fig. 6 on said rear closing plate 56, are two curved springs 57 and 58. These curved springs 57 and 58 are each retained in position by means of a screw 59 and are positioned adjacent the lug 52 in such a manner that as the pin 55 engages said lug 52, it will pass between the springs 57 and 58 in contact therewith as shown in Fig. 7.

The screws 59 which secure the spring members 57 and 58 in position on the rear closing plate 56, project through said closing plate 56 as indicated by the reference character 60 and provide the terminals or binding posts for the wires 70 of the ignition circuit.

Assuming that the valve member 15 is in the position shown in Fig. 2 and the several parts of the locking mechanism are in their secured positions, the operation of the device is as follows:

The plate 33 is elevated and a key inserted into the keyhole slot 32. Upon turning the key in the slot 32, the lock member 31

will be rotated and through the medium of the cam 46, the reciprocating member 40 will be withdrawn from the recess 41 to the position which will permit of a free turning of the rotating member 21 within the housing 20. After the reciprocating member 40 has been disengaged from the recess 41, the rotating member 21 is free to move and upon rotation thereof, the locking member 24 and the flexible shaft 27 serve to lift the valve 15 to a position where the outlet 12 will be opened to permit of a free passage of fuel through the fuel line 10.

Simultaneously with this operation, the pin 55 passes between the springs 57 and 58 and completes the electrical circuit in order that proper ignition may be had. After this operation takes place, the key is rotated backwardly to a position where the cam is moved to the position shown in Fig. 4. In this position, however, owing to the fact that the rotating member 21 has not been moved, the free end of the reciprocating member 40 will engage the inner wall of the housing 20 and will not interfere with the proper rotation of the member 21.

When it is desired to lock the motor, it will only be necessary to grasp the thumb pieces 22, rotate the rotary member 21 anti-clockwise until it reaches such a position that the end of the reciprocating member 40 will enter the recess 41 and hold all of the parts in their locked position. Simultaneously with this operation, the pin 55 will pass from between the springs 57 and 58, thus breaking the electrical circuit and rendering the ignition system of the motor inoperative.

It is to be understood that the terminals 60 of the wire 70 of the ignition circuit may be suitably insulated in order that the proper results may be had.

While in the present instance the invention has been described as pertaining particularly to motors for motor vehicles, it is obvious that the same is capable of use in connection with fluid lines and electrical circuits generally and is not limited to use in controlling the supply of fuel and current to internal combustion motors.

Claims:

1. A device of the character described comprising a housing, a tubular extension projecting from said housing, a valve mounted in said tubular extension, a rotatable member mounted in said housing, a plurality of oppositely disposed stops rigidly carried by the housing, a pin carried by said rotatable member and adapted to engage either of said stops to limit the rotary movement of said rotatable member, and a plurality of electrical contacts mounted in said housing, the pin carried by the rotatable member being adapted to engage said electrical contacts to complete an electric

circuit therebetween when said pin is in engagement with one of said stops.

2. In a device of the character described, a housing, a tubular extension projecting therefrom, a valve mounted in the tubular extension, a member rotatably mounted within the housing, means connecting said rotatable member and said valve whereby the valve is operated upon rotation of the 10 rotatable member, means carried by the rotatable member and adapted for engagement with the housing to prevent movement of the rotatable member, key-actuated means for operating said locking means to release the rotatable member, stops carried by said housing, and a pin carried by the rotatable member for engagement with said stops to limit the rotary movement of said rotatable member.

20 3. A device of the character described comprising a housing, a rotatable member mounted therein, a tubular extension projecting therefrom, a valve mounted in said tubular extension, means connecting the rotatable member with the valve whereby the valve will be moved to open and closed position upon movement of the rotating member, means normally holding said rotatable member against movement, means for releasing said holding means, a plurality of contacts mounted interiorly of the housing, said contacts comprising resilient members, and means carried by the rotatable member and adapted to engage between the contacts 30 35 when the rotating member is moved to operate the valve to open position, said means serving as a stop to limit the rotary movement of said rotatable member in both directions.

40 4. A device of the character described comprising a housing, a bolt receiving recess formed therein, a plurality of oppositely disposed stops carried by the housing, a plurality of resilient circuit contacts rigidly carried by the housing, a rotatable member, a bolt carried by the rotatable member and adapted for engagement in the bolt-receiving recess, and a pin carried by the rotatable member and adapted to limit 45 the rotary movement thereof by engagement with one or the other of the stops of the housing, said pin being adapted to complete

an electric circuit between the resilient contacts upon engagement with one of said stops.

55 5. A device of the character described comprising a housing, a tubular extension projecting therefrom, a valve mounted in said tubular extension, a rotating member mounted with the housing, means carried by the rotating member and connected to the valve for operating the same upon rotary movement of the rotating member, a plurality of contacts mounted internally of the housing, a plurality of oppositely disposed lugs mounted in the housing, and means carried by the rotating member and adapted to engage the contacts to complete an electric circuit upon movement 60 65 of the rotary member in one direction and adapted to disengage the contacts upon movement of the rotating member in the opposite direction, said means being adapted to alternately engage said lugs to limit the movement of the rotating member.

70 6. A device of the character described, comprising a housing, a tubular member projecting therefrom, a valve mounted in said tubular member, a rotatable member mounted in said housing, a valve stem projecting from said valve, a link pivotally connected to said rotatable member and to said valve stem whereby upon rotation of the 75 rotatable member the valve will be operated, a sliding bolt for locking said rotatable member against movement, and a rotatable cam member for releasing said sliding bolt.

75 7. A device of the character described comprising a housing, a rotatable member mounted in said housing, a valve, means connected to said valve and to said rotary member whereby upon rotation of said rotatable member said valve will be operated, a plurality of stops carried by said housing, a plurality of contacts carried by said housing, and a lug carried by said rotatable member and adapted to engage said stops to limit the movement of said rotatable member, said lug being adapted to establish connection 80 85 90 95 100 between said contacts when in engagement with one of said stops.
